UNITED STATES PATENT OFFICE.

GEORGE HARTJE, OF NEW YORK, N. Y.

DESIGN FOR JEWELRY.

SPECIFICATION forming part of Design No. 12,075, dated December 21, 1880.

Application filed November 9, 1880. Term of patent 7 years.

To all whom it may concern:

Be it known that I, GEORGE HARTJE, a citizen of the United States, residing at New York, in the county and State of New York, have invented and produced a new and original Design for Jewelry, of which the following is a specification, reference being had to the accompanying drawing, forming part thereof.

My design consists in the combination of a representation of the moon with that of a cow, the cow being shown in the act of jumping over the moon.

The accompanying drawing shows a front view of my design.

In this drawing the letter A designates the representation of the moon, and B designates the representation of a cow in the act of jumping over the moon.

In the example represented by the drawing

my design is shown as applied to a scarf-pin; 20 but it is obvious that the same can be applied with equal advantage to breast-pins, ear-rings, lace-pins, and other articles of jewelry.

What I claim as new, and desire to secure by Letters Patent, is— 25

A new ornamental design for jewelry, consisting of a representation of the moon in combination with the representation of a cow, the cow being shown in the act of jumping over the moon, as shown and described.

In testimony whereof I have hereunto set my hand and seal in the presence of two subscribing witnesses.

GEO. HARTJE. [L. S.]
